UNITED STATES PATENT OFFICE

151,235

DESIGN FOR A TRAILER VEHICLE

Gerald J. Harman, Beverly Hills, Calif.

Application August 15, 1946, Serial No. 132,555

Term of patent 7 years

(CL. D14—3)

To all whom it may concern:

Be it known that I, Gerald J. Harman, a citizen of the United States, residing at Beverly Hills, in the county of Los Angeles and State of California, have invented a new, original, and ornamental Design for Trailer Vehicle, of which the following is a specification, reference being had to the accompanying drawing, forming a part thereof, and in which:

Fig. 1 is a perspective view of the trailer vehicle showing my new design.

Fig. 2 is a front elevational view of the trailer vehicle.

Fig. 3 is a rear elevational view of the trailer vehicle.

I claim:

The ornamental design for a trailer vehicle, as shown.

GERALD J. HARMAN.
